UNITED STATES PATENT OFFICE

149,037

DESIGN FOR A WOVEN PLASTIC FABRIC

George Backer, New York, N. Y.

Application September 25, 1947, Serial No. 141,576

Term of patent 14 years

(CL. D92—1)

To all whom it may concern:

Be it known that I, George Backer, a citizen of the United States of America residing in New York city, county of Kings, State of New York, have invented a new, original, and ornamental Design for a Woven Plastic Fabric, of which the following is a specification, reference being had to the accompanying drawing, forming a part thereof.

The figure of the drawing is a face view of a woven plastic fabric showing my new design. The dotted lines outline a design unit, which unit is repeated over the fabric as indicated by the extensions beyond the unit boundaries.

I claim:

The ornamental design for a woven plastic fabric, as shown and described.

GEORGE BACKER.
